UNITED STATES PATENT OFFICE.

PAUL BROWN KLUGH, OF CHICAGO, ILLINOIS, ASSIGNOR TO THE CABLE COMPANY, OF CHICAGO, ILLINOIS, A CORPORATION OF ILLINOIS.

COVER FOR CONTROLLING DEVICES OF MECHANICAL MUSICAL INSTRUMENTS.

No. 903,294.

Specification of Letters Patent.

Patented Nov. 10, 1908.

Application filed June 7, 1907. Serial No. 377,685.

To all whom it may concern:

Be it known that I, PAUL BROWN KLUGH, a citizen of the United States, residing at the city of Chicago, in the county of Cook and State of Illinois, have invented a certain new and useful Cover for Controlling Devices of Mechanical Musical Instruments, of which the following is a specification, reference being had therein to the accompanying drawings.

My invention comprises means for alternately concealing and exposing the manually operable devices for controlling the tempo, expression and other mechanisms of self-playing musical instruments and has for its two principal objects, first, when in closed position, to provide a neat and suitable cover for the above mentioned devices; and second, when open, to expose and allow access to them for manipulation and provide a substantial and convenient support for the wrists of the operator.

Another object of my invention is to provide means through which the support for the wrists will be rendered adjustable in any desired degree of forward motion without in any manner sacrificing strength or solidity.

I have shown the device in the drawings as applied to a piano which is provided with the usual keys for manual playing and also with interior automatic-playing mechanism; wherein

Figure 1 is a sectional end view of the forward end of a piano key-table, showing the device in closed position and acting therein as a cover for the finger-grip of one of a possible series of controlling levers; and Fig. 2 is a view similar to Fig. 1, showing the device in open position and acting therein as a rest for the hands or wrists. Fig. 3 is a perspective view of the device in extended or open position, showing the convenient location of the rest supplied for the wrists of the operator during manipulation of the exposed finger-grips.

The interior construction of these instruments is so well known that description thereof is unnecessary and it may be sufficient to say that the automatic mechanism therein contained is under the control of the operator by means of a series of controlling levers which usually extend to a position convenient for manipulation at the forward edge of the key-table and are provided with upwardly turned finger-grips. (As shown at 5).

Instruments of this class are usually provided with openings in the upper and lower front-boards or panels, through which access may be had to other parts concerned in the automatic operation, and these openings are adapted to be closed to conceal such parts when not in service. In pursuance of this object for concealment of parts identified with the automatic playing-mechanism, I have provided a novel and simple device for concealing the otherwise exposed ends of the controlling-levers.

1 represents the conventional piano key-table, 2 the key-slip or lock-rail, 3 the piano keys, 4 the forward key-rail, and 5 the handles or finger-grips at the forward ends of the controlling-levers.

In my preferred form of construction, the key-slip 2 ends at a point upon each side of the controlling-levers 5 which project forwardly into the space thus allowed, and I have provided a cover for them in the shape of a movable section 6. This section is recessed upon the inner side and when closed (Fig. 1) completely conceals the levers and acts as a continuation of the key-slip 2.

At the point 9 I rigidly attach the horizontal guide and support bars 8 by riveting the upturned ends thereof to a substantial plate, which is in turn securely screwed to the inner surface of the recess.

I provide in the key-table 1, two grooves or channels 7 which extend rearwardly from a point located far enough forward of the face of the key-rail 4 to allow admission and withdrawal of the two support-bars 8.

When the cover 6 is closed, the forward ends of the supports 8 rest upon the surface of the key-table 1 and extend rearwardly under the keys for a considerable distance before bending sharply downward into and continuing in the closely fitting grooves 7. When, however, the cover 6 is drawn into open position, the operation will cause the support 8 to slide horizontally forward in the grooves 7 until the bends 10 in the said supports stop against the forward ends of the grooves. The support-bars 8 are of substantial thickness and the grooves 7 are cut sufficiently deep to allow the rear portion of the bars to pass freely beneath clamps 11 which are screwed firmly in position upon the key-table across the grooves. It is necessary that while these clamps allow free lengthwise movement of the supports in the

grooves there should not be at any time lost motion, and I have provided preventive means for this by locating in the groove beneath each bar 8 a spring 12 which bears upwardly under the bar and insures close relation at all times between the bar and the clamp. Downward pressure upon the open cover or rest will be firmly resisted by the supports as the bearing surfaces are always in contact.

I am aware that many modifications of this invention may be devised by those skilled in the art and I do not wish to limit myself to the exact construction herein demonstrated, but

What I do claim and desire to secure by Letters Patent is:

1. In a musical instrument, the combination of a key-table, keys above said table, a rail above said table and near the forward end of said keys and means attached to said rail and movably supported by said table to support said rail for horizontal movement.

2. In a musical instrument, the combination of a key-table, a key-slip section and means attached to said section and slidably supported by said key-table to support said section for horizontal movement.

3. In a mechanical musical instrument, the combination of controlling devices and a cover mounted for horizontal movement rearwardly toward said devices to conceal them and forwardly from said devices to expose them.

4. In a mechanical musical instrument, the combination of controlling devices, a table, a hand-rest, and means rigidly secured

to said hand-rest and slidably supported by said table to support said hand-rest for horizontal movement into and from close proximity to said controlling-devices.

5. In a mechanical musical instrument, the combination with a key-table, controlling devices and a cover for concealing them, of recesses within said key-table and supporting means attached to said cover and acting within said recesses to movably support said cover for the purposes described.

6. In a mechanical musical instrument, the combination with a key-table, controlling devices and a rest adapted to be moved toward and from said devices, of recesses within said key-table and supporting means attached to said rest and acting within said recesses to movably support said rest for the purposes described.

7. In a player piano, the combination with the key slip having a cut away portion, of the expression or action levers in the space formed by said cut away portion, a cover casing having sliding movement and designed to fit the cut away portion when closed, and a support therefor designed to allow the cover casing being withdrawn to uncover the expression levers as and for the purpose specified.

Signed at Chicago, Illinois, this twenty-ninth day of May, 1907, in the presence of two subscribing witnesses.

PAUL BROWN KLUGH.
